UNITED STATES PATENT OFFICE

DENNIS PARKS, OF ST. LOUIS, MISSOURI

METHOD OF AND MACHINE FOR BUILDING HEELS

Application filed July 26, 1928, Serial No. 295,395. Renewed August 21, 1930.

This invention relates to improvements in heel-building machines of the general type illustrated in my pending application Ser. No. 262,424, filed March 17th, 1928, now 5 Patent Number 1,740,871, dated December 24, 1929.

The general object of the invention is to provide improved means for forming the heel when using either whole or pieced lifts, 10 and to provide improved means for driving one or more nails through the lifts just before they are put under final pressure in the heel chute or pressure container.

The improved means for forming the heel 15 comprises a pair of plates between and in engagement with which the heel is built up in the usual way, with means for automatically forcing said plates toward each other, or into firm engagement with the opposite 20 sides of the heel-blank, to hold the lifts in fixed relation to each other as the heel-blank is forced into engagement with a previously formed heel-blank and into a pressure container for the heel-blanks.

25 The means for nailing the assembled lifts finds its embodiment in a sliding carriage comprising two relatively movable parts, one upon which the heel-blank is built up and the other containing the nailing mechanism, 30 with means for moving said carriage in a direction to bring the built-up heel-blank into engagement with a previously formed heel-blank in a container, whereby the motion of that portion of the carriage will be 35 temporarily arrested, and the other part of the carriage containing the nailing mechanism will be advanced to drive the nail into the heel-blank.

40 The invention is illustrated in the accompanying drawings, in which—

Figure 1 is a view in side elevation of a heel-building machine of the type referred to having my improvements applied thereto;

45 Figure 2 is a view in rear elevation of the same, the upper part being broken away;

Figure 3 is a broken view in side elevation on an enlarged scale showing the carriage slidably mounted on an extension of the bed- 50 plate of the heel-blank container and with a

built-up heel-blank in position between the heel-forming plates;

Figure 4 is a cross-sectional view on the line 4—4 of Fig. 3, and also on the line 4—4 of Fig. 1, on an enlarged scale as respects 55 the latter figure, showing the heel-forming plates in normal position corresponding to the position of the parts in Fig. 3;

Figure 5 is a view similar to Fig. 3, but showing the carriage advanced to bring the heel-blank into engagement with an equalizing plate in a pressure container or holder for the heel-blanks and with a nail driven 60 through the assembled lifts by the nailing mechanism;

Figure 6 is a view taken on the line 6—6 of Fig. 5 showing the position of parts which have been moved by the advance of the sliding carriage to turn the heel-forming plates into engagement with the opposite sides of the assembled heel lifts; and 70

Figure 7 is a top plan view of the carriage illustrating more particularly the adjustable mounting of the heel-forming plates thereon.

Referring now to Figs. 1 and 2 of the drawings, the numeral 1 indicates the main frame of the machine, the top portion of which is inclined forwardly as shown and has supported thereon a combined heel-log container and race-way. The race-way is indicated at 2 and comprises two parallel bars having rounded connections at either end and provided with a continuous slot 3 (Fig. 5) in which are slidably mounted the heads 4 of a set of equalizing plates 5. Below the race-way and parallel with the lower side thereof is a bed-plate 6 which co-operates with the lower member 7 of the race-way to provide a pressure container for heel-blanks forced therein. The plate 6 is what is known in the art as a breast plate; that is to say, the breasts of the heels rest upon it as they pass through the container. The bed-plate 6 has a portion extending forwardly beyond the lower end of the race-way 2, which extending portion is indicated at 8, and which serves as a table for supporting the heel lifts as they are assembled to form a heel-blank 9 (Fig. 1) and which also serves to oper- 100

atively support a sliding carriage indicated generally by the numeral 10. This carriage is formed in two main parts, namely, a head 11 and a heel-former 12. The head 11 is hollow for a portion of its length and houses one end portion of a coil spring 13 the end of which bears against the heel-former 12. Adjustably mounted in the rear end of the head 11 by means of a screw 14 is a nail driver 15 which operates in a tubular guide 16 secured in the back-plate 17 of the heel-former 12 by means of a set-screw 18. Projecting from the bottom of the head 11 is an arm 19 (Figs. 1, 3 and 5) which is secured to the forward end of an actuating bar 20. Secured to the forward end of this actuating bar is a chain 21 which passes over a pulley 22 and then is extended downwardly and secured at its end to a drum 23 which forms the hub of one member of a ring clutch shown in detail in Fig. 2. The drum 23 is loosely mounted on a shaft 24 which is adapted to be continuously rotated from a pulley 25. Mounted on the inner end of the drum 23 is a ring member 26 which is opposed to a corresponding ring member 27 which is fast on the shaft 24. The drum 23 is provided on its outer end with inclined surfaces 28 which engage corresponding surfaces of a fixed cam member 29 mounted on one leg of the frame 1. Projecting radially from the drum 23 is an arm 30 to which is pivotally secured the upper end of a connecting rod 31, the lower end of which is connected to a treadle 32 intermediate the point of pivotal connection 33 of the treadle on the frame and its inner end. By pressing downwardly on the inner end of the treadle, its opposite end will be raised, thereby lifting the arm 30 and turning the drum 23 so that the engagement of the inclined surfaces 28 and 29 will force the drum to the right, as shown in Fig. 2, bringing the clutch member 26 into engagement with the clutch member 27 and thereby causing the drum 23 to be rotated to wind the chain 21 thereon. This, of course, pulls the chain downwardly over the pulley 22 and draws the sliding head 11 toward the heel-former 12, after which the carriage 10 as a whole will be moved upwardly over the bed 8 to carry the heel-blank built up in the heel-former into the heel-blank container.

In order to automatically arrest this movement of the carriage after it has travelled the required distance to perform the functions hereinafter described, I adjustably secure on the vertical run of the chain 21 a stop 34 which is adapted to engage in its downward movement the upper end of a rod 35 slidably supported in a guide 36 mounted on the frame and pivotally connected at its lower end to the inner end of the treadle 32, as indicated at 37. As the chain is wound upon the drum 23 to advance the carriage 10, the stop descends and engages the upper end

of rod 35 and thereby locks the clutch against further rotation. That is to say, any further downward movement of the stop 34 would move the inner end of the treadle 32 downward and open the clutch members 26 and 27. This assumes that the operator would maintain pressure on the treadle by holding his foot thereon, in which event no harm could occur, for as soon as pressure was exerted by the foot to close the clutch, the stop 34 would move the rod 35 downward to open the clutch. In practice, the stop is adjusted to engage the upper end of the rod 35 synchronously with the arrival of the carriage 10 at the desired limit of its upward movement, and as this brings such movement to a stop, the operator learns to remove his foot from the treadle at this time, whereupon the inner end of the treadle will fall by gravity to release the clutch and the carriage 10 will slide backward by gravity over the bed 8 to its position at the bottom end of said bed, or that position shown in Fig. 1.

To arrest the return movement of the parts when they have reached the desired position, I provide a stop 38 on the outer side of the clutch member 26 which is adapted to engage with the inner end of an adjustable stop bar 39 which has a screwthreaded portion 40 mounted on the frame and provided with a lock-nut 41, whereby the stop bar 39 can be positioned to be engaged by the stop 38 to stop the carriage 10, the clutch member 26 and the treadle 32 at the respective positions thereof desired.

In the forward movement of the carriage 10, my novel heel-forming plates are automatically actuated and, when desired, a nail is driven into the assembled heel-blanks and the construction and operation of these parts will now be described.

Projecting inward from each side of the back-plate 17 of the heel-former are two shafts 42 on each of which is pivotally mounted a circular head 43 having a depending arm 44 on the lower reduced end 46 of which is mounted a roller 45. As thus mounted, the arms 44 are rocker arms, being adapted to rock on the shafts 42. They are held in their normal or vertical position, or that shown in Fig. 4, by means of a coil spring 47 the opposite ends of which are connected to the lower ends 46 of the arms 44. This spring maintains the rollers 45 in contact with the opposite sides of a slide bar 48 which is secured to the underside of the arm 19 of head 11 by means of screws 49. In the normal position of the rocker arms 44, the rollers 45 rest in circular depressions 50 formed, respectively, in the outer sides of the slide bar near the inner ends thereof, this position of the rollers being shown in Figs. 1, 3 and 4. Projecting upward from each of the circular heads 43 of the rocker arms 44 is a support 51 on which is adjustably mount-

ed a heel-forming plate 52 which, for the purpose of adjustment, is provided with slots 53 (Fig. 7) and is secured on the support 51 by binding screws 54 passing through said slots and engaging in the support 51. 5 Each of the plates 52 is of the shape, as shown, to embrace snugly the side of the heel-blank, and each of them has a depending lug 55 (Figs. 4 and 6) which is adapted to be engaged by the inner end of a set-screw 56 mounted in the support 51, which screws may be used in adjusting the heel-forming plates inwardly when the screws 54 are loosened and which, together with the screws 54, serve to maintain the plates 52 in their adjusted positions. 10

The tubular guide 16 previously referred to (Fig. 3) is bored centrally to provide a container 57 for nails, and in this container a nail is adapted to be inserted when desired, 20 to be forced into the assembled heel-blanks by the nail driver 15. The tubular member 16 with its bore for a nail constitutes a nail guide and will hereinafter be referred to by that name. 25

In operation, after a nail has been inserted in the nail guide 16 and the lifts 9 have been assembled into a heel of the desired height on the extension 8 of the bed-plate 6 between the heel-forming plates 52, the operator steps on the pedal 32 which causes the clutch members 26 and 27 to engage, whereby the chain 21 will be wound upon the drum 23. This causes the sliding carriage 10 to be moved inward to force the heel into the container or heel chute formed by the bed-plate 6 and the lower member 7 of the race-way 2. As soon as the heel-blank 9 strikes the column of heels already in the container, the heel-former 12 as a whole will have its motion temporarily arrested. The sliding head 11, however, to which the power is applied by the chain 21 continues its inward movement, compressing the spring 13. The resulting motion of the sliding head 11 relative to the heel-builder 12, or in other words, the inward movement of the slide bar 48, causes the rollers 45 to ride out of the depressions 50 therein, which causes the rocker arms 44 to pivot, and turns the heel-forming plates 52 into firm engagement with the sides of the lifts, forcing them into their proper position. At the same time, this motion of the head 11 relative to the heel-former causes the nail driver 15 to force a nail through the assemblage of lifts. This position of the parts is shown in Fig. 5, the nail being dotted and indicated by the numeral 58. After the nail has been driven and the spring 13 fully compressed, the carriage 10 as a whole continues its inward movement and forces the entire column of heel-blanks, including that just nailed, as described, forward in the pressure container. After completing its stroke, 60 which is regulated by the engagement of the

stop 34 on chain 21 with the upper end of the rod 35 mounted on the inner end of treadle 32, the head 11 returns by gravity to the position shown in Fig. 1, the spring 13 forces the heel-former 12 to its normal position, the rollers 45 drop back into the depressions 50, and the heel-forming plates return to their normal positions for receiving the next set of lifts to be assembled into a heel. 70

It will be seen from the above description that the heel-forming plates exert their pressure on the lifts at the moment the nail driver begins to force the nail into the lifts. This makes it certain that the lifts are in proper position when the nails go through them. After the nail has been driven, the lifts are, of course, thereby held in proper position as they proceed through the pressure container. It should be understood, however, that my improved heel-forming plates are of great value if a nail is not used, since they insure the proper positioning of the lifts at the time they go under pressure in the container. 80

It will be observed that the movement of the heel-forming plates toward each other is such that they not only exert an inward pressure on the lifts but also a downward pressure. This is of great importance when a heel is being built that involves the use of wedged lifts. It has been found that at the moment this character of heel enters the pressure container, the wedged lifts, if not restrained, tend to squeeze out toward the top of the heel, thus causing the heel to be improperly shaped. With the use of my improved forming plates, such wedged lifts are held down firmly in place until either the nail has been driven through or until complete pressure has been put upon them. 90

Still another advantage of the heel-forming plates is apparent when pieced heels are being built. With such heels, the joints between the pieces are approximately vertical, as shown by the dotted lines in Fig. 6, and it is of the utmost importance that the joints be closed up tightly, and this is very effectively done by the heel-forming plates herein described. 100

The nail-driving mechanism is designed as an improvement over the nail driving mechanism described and claimed in a pending application of Fred Hawkins, Ser. No. 258,157, filed March 1st, 1928, which utilizes the forward motion of the building head to drive the nail. The nail is driven simultaneously with the movement of the heel toward the pressure container by means of mechanism that moves the nail driver forward faster than the movement of the building head proper. The present device is much simpler and utilizes a different principle, in that the heel is not in motion at all at the time the nail is driven, but is at a dead stop, and hence in the ideal position for having the nails driven into the lifts. 110

The motion of the sliding head 11 which drives the nail is a continuation of its inward movement necessary to force the heel-blank into the pressure container, and the operation 5 is thus direct and positive and the machine itself simpler in organization and operation.

It will be understood that the heel-forming plates used will be adapted to conform to the shape of heel being made. The drawings 10 show plates adapted for use in making decked heels and their engaging faces are inclined to correspond with the incline of the sides of the heel-blank. If a different character of heel were being made, the plates would either be 15 correspondingly adjusted or a set of plates adapted for the particular character of heel being made would be substituted for those shown.

As in the case of the machine of the Hawkins application above referred to, it will be understood that a nail-driver could be employed that would drive two nails instead of a single nail.

I direct attention to the fact that when a 25 tapered heel is being built, as shown in the drawings, the heel-forming plates are shaped or positioned in a manner to receive the small or top lifts first. I have found that the heel can be built in this way much faster than by 30 putting in the base lift first. Another advantage of this is that it enables the nail to be driven through the heel from the top lift instead of from the base lift, which is the desirable way of nailing the heel. A final 35 advantage of building the heel by inserting the small or top lift into the heel-former first is that it enables the heel to be forced into the pressure container with the big or base lift in advance. The reverse arrangement would 40 make it exceedingly difficult to withdraw the heel-forming plates from contact with the heel-lifts at the time the carriage starts back toward the building position. Of course, in building a straight heel, the lifts are of the 45 same size and in that case the heel-forming plates would have their faces parallel.

Finally, I wish to state that while my improved heel-forming and nailing devices are primarily designed for use with a heel-building 50 machine of the type shown, having an inclined pressure container, the invention is not limited to use in such a machine. It would be equally valuable in connection with a machine in which the pressure container 55 were arranged in a horizontal instead of an inclined position.

I claim:

1. In a machine for building heels, a 60 slideable carriage, a heel-former carried thereby having heel-forming plates mounted thereon and normally positioned to freely receive the lifts being assembled into a heel, a pressure container adapted to have heels forced therein by said heel-former, and movable means 65 mounted on said carriage and operating in

the forward movement thereof to positively force the plates toward each other to exert pressure on all the lifts of the heel and thereby properly position them before the heel is forced into the container.

2. In a machine for building heels, a slideable carriage, a heel-former carried thereby having heel-forming plates pivotally mounted thereon and normally positioned to freely receive the lifts being assembled into a heel, a pressure container adapted to have heels forced therein by said heel-former, and movable means mounted on said carriage and operating in the forward movement thereof to positively force the plates toward each other and downward to exert pressure on all the lifts of the heel to thereby properly position them and to hold them firmly in place against the tendency to upward movement until the complete pressure of the heel-former has been exerted to force them into the pressure container.

3. In a machine for building heels, a slideable heel-former having heel-forming plates pivotally mounted thereon on horizontal axes, and normally positioned to freely receive the lifts being assembled into a heel, a pressure container adapted to have heels forced therein by said heel-former, and automatic means operating in the movement of said heel-former toward said pressure container to turn said plates toward each other on their pivots and cause them to exert pressure on all the lifts of the heel and thereby properly position them before the heel is forced into the container.

4. In a machine for building heels, a slideable heel-former comprising a back-plate and a pair of rocker arms pivotally mounted on said back-plate on horizontal axes, a pair of heel-forming plates mounted, respectively, on the upper sides of said rocker arms and positioned to freely receive the lifts being assembled into a heel, a pressure container adapted to have heels forced therein by said heel-former, and movable means operating in the movement of said heel-former toward said pressure container to engage and rock said rocker arms and cause said heel-forming plates to be forced toward each other to exert pressure on all the lifts of the heel and thereby properly position them before the heel is forced into the container.

5. In a machine for building heels, a slideable heel-former comprising a back-plate, a pair of rocker arms pivotally mounted thereon on horizontal axes, a pair of heel-forming plates mounted, respectively, on the upper sides of said rocker arms and normally positioned to freely receive the lifts being assembled into a heel, a pressure container adapted to have heels forced therein by said heel-former, and automatic means operating in the movement of said heel-former toward the pressure container to separate the lower

ends of said rocker arms and thereby force the heel-forming plates toward each other to cause them to exert pressure on all the lifts of the heel and thereby properly position them before the heel is forced into the container.

6. In a machine for building heels, a slide-
10 able heel-former comprising a back-plate, a
pair of rocker arms pivotally mounted thereon
on horizontal axes, a pair of heel-forming
plates mounted, respectively, on the upper
sides of said rocker arms and normally posi-
15 tioned to freely receive the lifts being assem-
bled into a heel, a roller mounted on the
lower end of each of said rocker arms, a pres-
sure container adapted to have heels forced
20 therein by said heel-former, a sliding head
operatively associated with said heel-former,
means operable at will for moving said head
toward said heel-former and both of said
25 parts toward the pressure container, and a
slide plate movable with said head and hav-
ing on its opposite sides surfaces adapted to
engage said rollers and move them outward
30 in the movement of said head toward said
carriage, whereby to force the heel-forming
plates toward each other and cause them to
exert pressure on all the lifts of the heel and
thereby properly position them before the
35 heel is forced into the container.

7. In a machine for building heels, a slide-
35 able heel-former having heel-forming plates
pivotally mounted thereon and normally po-
sitioned to freely receive the lifts being as-
sembled into a heel, a pressure container
40 adapted to have heels forced therein by said
heel-former, means for moving the heel-former
toward said pressure container comprising a
slidable head movable toward and into
45 engagement with said heel-former, and means
carried by said head and operating in the
movement of said head toward the heel-former
to force the heel-forming plates toward
each other to cause them to exert pressure on
50 all the lifts of the heel thereon and thereby
properly position them before the heel is
forced into the container.

8. In a machine for building heels, a slide-
55 able heel-former having heel-forming plates
normally positioned to freely receive the lifts
being assembled into a heel, a pressure con-
tainer adapted to have heels forced therein
by said heel-former, a sliding head located to
60 the rear of said heel-former and held in sep-
arated relation therewith by a spring, a nail
guide mounted in said heel-former, a nail
driver carried by said head and working
65 in said nail guide, means operable at will for
moving said head toward said heel-former
and both of said parts toward said pressure
container, whereby when the heel-former is
arrested by engagement of the assembled
70 lifts thereon with a heel-blank in the pressure
container, said head will be advanced to force
the nail through said assemblage of lifts and

then to force the resulting heel-blank into
the container, and automatic means operating
in the forward movement of said head to force
70 said plates toward each other to cause them
to exert pressure on all the lifts of the heel on
the heel-former and thereby properly position
them before the heel is forced into the
75 container.

9. In a machine for building heels, a bed-
plate, a heel-former slidably mounted thereon
and having movable heel-forming plates, a
head slidably mounted on said bed-plate at
the rear of said heel-former, a spring inter-
80 posed between said head and heel-former, a
pressure container adapted to have heels
forced therein by said heel-former, means
operable at will for moving said head toward
85 and into contact with said heel-former and
both of said parts toward said pressure con-
tainer, and means carried by said head and
operating in the movement of the head to-
ward said heel-former to move said plates
90 toward each other to cause them to exert pres-
sure on all of the lifts of the assembled heel
and thereby properly position them before
the heel is forced into the container.

10. In a machine for building heels, a bed-
plate, a heel-former slidably mounted thereon
comprising a pair of rocker arms each of
which carries a heel-forming plate, a roller
95 mounted on the lower end of each of said
rocker arms, a head slidably mounted on said
bed-plate, a pressure container adapted to
have heels forced therein by said heel-former,
means operable at will for moving said head
100 toward said heel-former and both of said
parts toward said pressure container, and a
slide plate carried by said head and operat-
ing between said rollers, said slide plate hav-
ing depressions in which said rollers nor-
105 mally rest, whereby when the head is ad-
vanced toward said heel-former, said depres-
sions will be moved beyond the rollers caus-
ing the latter to be separated and thereby
turn the heel-forming plates toward each
110 other on their pivots and cause them to exert
pressure on all the lifts of a heel assembled
between them, and thereby properly position
said lifts before the heel is forced into the
115 container.

11. In a machine for building heels, a
120 slideable heel-former comprising a back-
plate and a pair of rocker arms pivotally
mounted on said back-plate on horizontal
axes, a pair of heel-forming plates mounted,
respectively, on the upper sides of said
125 rocker arms, a coil spring connecting the
lower ends of said rocker arms and normally
holding said heel-forming plates in a posi-
tion to freely receive the lifts being assem-
bled into a heel, a pressure container adapted
130 to have heels forced therein by said heel-
former, and automatic means operating in
the movement of said heel-former toward
the pressure container to separate the lower

ends of said rocker arms and thereby force the heel-forming plates toward each other to cause them to exert pressure on all of the lifts of the heel, and thereby properly position them before the heel is forced into the container.

12. In a machine for building heels, a slideable heel-former for receiving the lifts being assembled into a heel, a pressure container adapted to have heels forced therein by said heel-former, a sliding head located to the rear of said heel-former, a nail guide mounted in said heel-former, a nail driver carried by said head and working in said nail guide, and means operable at will for moving said head toward said heel-former and both of said parts toward said pressure container, whereby when the heel-former is arrested by engagement of the assembled lifts thereon with a heel-blank in the pressure container, said head will be advanced to force the nail through said assemblage of lifts and then to force the resulting heel-blank into the container.

13. In a machine for building heels, a slideable heel-former for receiving the lifts being assembled into a heel, a pressure container adapted to have heels forced therein by said heel-former, a sliding head located to the rear of said heel-former and held in separated relation therewith by a spring, a nail guide mounted in said heel-former, a nail driver carried by said head and working in said nail guide, and means operable at will for moving said head toward said heel-former and both of said parts toward said pressure container, whereby when the heel-former is arrested by engagement of the assembled lifts thereon with a heel-blank in the pressure container, said head will be advanced to force the nail through said assemblage of lifts and then to force the resulting heel-blank into the container.

14. The method of building heels which consists in assembling lifts in heel-form, exerting pressure simultaneously on the sides of all of the lifts to properly position them, subjecting said lifts to a compression action, and maintaining the lateral pressure on said lifts until the compression action has been applied thereto.

15. The method of building heels which consists in assembling lifts in heel form, exerting pressure simultaneously on the sides of all of the lifts to properly position them, forcing a nail through said lifts while maintaining the lateral pressure thereon, subjecting said lifts to a compressing action, and maintaining the lateral pressure on said lifts until the compressing action has been applied thereto.

16. The method of building heels which consists in assembling lifts in a heel-former beginning with the smallest or top lift and ending with the largest or base lift, exert-

ing pressure simultaneously on both sides of all of the lifts to properly position them, subjecting said lifts to a compression action, and maintaining the lateral pressure on said lifts until the compression action has been applied thereto.

In testimony whereof, I have hereunto set my hand.

DENNIS PARKS.
